UNITED STATES PATENT OFFICE.

ORIEN A. JENISON, OF LANSING, MICHIGAN.

LATCH.

SPECIFICATION forming part of Letters Patent No. 399,268, dated March 12, 1889.

Application filed June 30, 1888. Serial No. 278,625. (No model.)

To all whom it may concern:

Be it known that I, ORIEN A. JENISON, of Lansing, in the county of Ingham and State of Michigan, have invented certain new and useful Improvements in Latches and Bolts Combined; and I do hereby declare the following to be a full, clear, and exact description of the invention, such as will enable others skilled in the art to which it appertains to make and use the same.

My invention relates to an improvement in latches and bolts designed more particularly for use on back doors of dwellings, outhouses, gates, &c., and has for its object to produce a latch which shall be simple in construction, effective in operation, and cheap to manufacture.

A further object is to provide a latch which may be quickly and easily locked and unlocked without the use of a key or other instrument.

A further object is to furnish a latch having a vibratory and reciprocating movement.

With these objects in view my invention consists in certain novel features of construction and peculiar combinations and arrangements of parts, as will be hereinafter set forth, and pointed out in the claims.

In the accompanying drawings, which illustrate an embodiment of my invention, Figure 1 is an elevation of a door and door-frame, showing my improved latch applied thereto. Fig. 2 is a view of a portion of a door with the casing-box removed, showing the parts in locked position. Fig. 3 is a view on the line *x x* of Fig. 1.

A indicates a door of any approved form of construction, and *B* the frame thereof, provided with a keeper, *a*.

Located on the inside face of the door in line with the keeper *a* is a latch-bar, *C*, having a widened portion, *b*, at its rear end, said widened portion being provided with two elongated slots, *c c*, one at each side of the portion *b*. The forward end of the latch-bar will be guided in its movements by a slotted plate, *B'*, secured to the edge of the door *A*.

Inserted between the rear end of the latch-bar *C* and the door *A* are two links, *D*, having outwardly-projecting pins *d*, adapted to work in the slots *c* when the latch is operated, as

presently explained. The links *C* are pivoted at their outer ends to the face of the door by means of screws or bolts *d'*, which secure a housing-box, *E*, thereto. This box *E* may be made of any preferred design, and is provided on its inner face with a flange, *f*, adapted to limit the rearward movement of the latch-bar *C*.

The latch-bar is provided at a suitable point between its ends with an L-shaped slot, *F*. A perforation, *g*, is made through the door within the space marked by the slot *F*, and has pivoted in it a lifting-lever, *G*, curved downwardly at one end in the usual manner and provided at its outer end with a thumb-piece. When the latch-bar is in its rearward position, the lifting-lever will be in the horizontal portion of the slot *F* under shoulder *s*, and therefore when said lifting-lever is operated the latch-bar will be raised out of the keeper *a*, and thus allow the door to be opened; but when it is desired that the door shall not be opened from the outside the latch-bar *C* is moved forwardly until the lifting-lever is in the vertical portion of the slot *F*, such movement being permitted by the link-connection of the latch-bar to the door, as previously explained.

If desired, a small knob or button, *h*, may be placed upon the latch-bar at any desired point, by which to slide the same back and forth. When the latch-bar *C* is in its forward position, as above explained, the lifting-lever will be free to move in the vertical portion of the slot *F*, and hence clear the shoulder formed by the horizontal portion of said slot, thereby preventing any movement of the lifting-lever from affecting the position of the latch-bar.

In order to prevent the latch-bar from being lifted from the outside by means of a tool inserted between the edge of the door and door-frame, said latch-bar is provided on its lower edge near its free end with short laterally-projecting flanges *i i*, adapted, when the bar *F* is moved to its forward position, to enter notches *i'*, made in the keeper *a*. By this construction it will be seen that the latch-bar *F* will be securely locked against vibratory movement.

Instead of pivoting the latch-bar to the door proper it may be mounted upon a suitable base-plate of any desired finish, which latter may be secured to the door. By pivoting the

latch-bar by means of links said bar may have a reciprocating as well as a vibratory movement.

The latch above described may be advantageously applied to stables, wood-houses, or back doors of dwellings, or to gates. It may also be made of ornamental design and applied to front doors of dwellings.

Slight changes might be made in the constructive details of my invention without departing from the spirit thereof; hence I do not wish to limit myself to the precise details of construction herein set forth; but,

Having fully described my invention, what I claim as new, and desire to secure by Letters Patent, is—

1. The combination, with longitudinally-adjustable latch-bar having a shoulder thereon, of a lifting-lever, the latter being so located that when the bar is adjusted longitudinally to one position the shoulder thereon is in a position to be engaged by the lifting-lever, so as to be lifted thereby, and when in another position the shoulder thereon is beyond the limit of movement of the lifting-lever, substantially as set forth.
2. The combination, with a door and door-

frame, of a latch-bar pivoted thereto by means of links, said bar being provided with a slot, a lifting-lever pivoted in the door and adapted to work in said slot, and a keeper secured to the door-frame, substantially as set forth. 30

3. The combination, with a keeper having a notch therein, of a latch having a vibratory and reciprocating movement and provided with a flange adapted, when the bolt is moved in one direction endwise, to enter the notch in the keeper, substantially as set forth. 35

4. The combination, with a door and door-frame, of a latch having a vibratory and reciprocating movement, a keeper secured to the door-frame, a housing-box to cover the pivoted portion of the latch-bar, and a flange on said housing-box to limit the rearward movement of the latch-bar, substantially as 40 45 set forth.

In testimony whereof I have signed this specification in the presence of two subscribing witnesses.

ORIEN A. JENISON.
